UNITED STATES PATENT OFFICE.

FRANCES A. SCHAEFER, OF NEW YORK, N. Y., ASSIGNOR TO JAMES R. KEISER, OF BROOKLYN, NEW YORK.

DESIGN FOR A STOCK.

SPECIFICATION forming part of Design No. 35,546, dated December 31, 1901.

Application filed August 20, 1901. Serial No. 72,710. Term of patent 3½ years.

To all whom it may concern:

Be it known that I, FRANCES A. SCHAEFER, a citizen of the United States, and a resident of the borough of Manhattan, city, county, and State of New York, have invented and produced a certain new and original Design for a Stock, of which the following is a specification, reference being had to the accompanying drawing, in which the figure is a perspective view of a stock showing my design.

The design in its entirety consists of a neck-band A, which appears from the front as a continuous band encircled by the ends B B', which gradually diminish in width as they approach each other at the front of the stock. The terminals B B' of the band cross each other at the point B², the band A being provided with a slit at that point. The termi-

nals B B' appear as connected with each other at the front by a bar or link C, studded with 20 the buttons C' C² C³. The heads of the buttons C' C² appear on the front of the terminals B B' and the button C³ appears between them, as plainly shown in the drawing.

The leading feature of the design consists 25 in the neckband A, the ends B B' of gradually-diminishing width encircling the same, and the connection between the terminals of the band.

What I claim is—

The design for a stock herein shown and described.

FRANCES A. SCHAEFER.
